US00D958109S

(12) **United States Design Patent** (10) **Patent No.:** **US D958,109 S**
Byrd et al. (45) **Date of Patent:** **** Jul. 19, 2022**

(54) **SPEAKER**

(71) Applicant: **Dolby Laboratories Licensing Corporation**, San Francisco, CA (US)

(72) Inventors: **Grayson H. Byrd**, San Francisco, CA (US); **Cody Michael Proksa**, San Francisco, CA (US); **Lucas E. Saule**, San Francisco, CA (US); **Peter Michaelian**, San Francisco, CA (US); **Brian Edward Renz**, Millbrae, CA (US); **John Carson Stewart**, San Francisco, CA (US); **Vincent Voron**, Menlo Park, CA (US)

(73) Assignee: **DOLBY LABORATORIES LICENSING CORPORATION**, San Francisco, CA (US)

(**) Term: **15 Years**

(21) Appl. No.: **29/794,817**

(22) Filed: **Jun. 15, 2021**

Related U.S. Application Data

(63) Continuation of application No. 29/675,792, filed on Jan. 4, 2019, now Pat. No. Des. 922,352.

(57) **CLAIM**

The ornamental design for a speaker, as shown and described.

DESCRIPTION

FIG. 1 is a front perspective view of a speaker showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate portions of the speaker that form no part of the claimed design.
